a corporation of New York

Application December 14, 1945, Serial No. 124,733

Term of patent 14 years

(Cl. D14—6)

To all whom it may concern:

Be it known that I, Benjamin Puttermann, a citizen of the United States, residing in Brooklyn, city of New York, county of Kings, and State of New York, have invented a new, original, and ornamental Design for Rearview Automobile Mirrors, of which the following is a specification, reference being had to the accompanying drawing, forming part thereof.

Fig. 1 is a front elevational view of a rear view automobile mirror showing my new design;

Fig. 2 is a side elevational view thereof; and

Fig. 3 is a rear elevational view of the rear view automobile mirror shown in Fig. 1.

I claim:

The ornamental design for a rear view automobile mirror, as shown.

BENJAMIN PUTTERMANN.
